UNITED STATES PATENT OFFICE.

WARREN F. FRASER, OF BOSTON, MASSACHUSETTS, ASSIGNOR TO FRASER MACHINE & MANUFACTURING CO., A CORPORATION OF MASSACHUSETTS.

LACING-HOOK-SETTING MACHINE.

No. 802,811.

Specification of Letters Patent.

Patented Nov. 3, 1908.

Application filed January 11, 1908. Serial No. 410,407.

To all whom it may concern:

Be it known that I, WARREN F. FRASER, a subject of King Edward VII, residing at Boston, in the county of Suffolk and State of Massachusetts, have invented new and useful Improvements in Lacing-Hook-Setting Machines, of which the following is a specification.

This invention relates to a machine for setting lacing hooks in the uppers of boots and shoes, particularly to that class of lacing hook setting machines in which the spacing of the hooks is done by the machine automatically and not by the operator.

15 The object of the invention is to provide a simple, rapid and durable machine of the class hereinbefore set forth.

The machine of this invention is designed and constructed in such a manner that the 20 operator places a right upper for a boot or shoe in a holder constructed therefor which is arranged to clamp the upper in position thereon. The operator then starts the lacing hook setting machine which is so constructed 25 that it moves relatively to the upper and longitudinally thereof, setting a series of lacing hooks in said right hand upper and then stops. The operator then removes this right hand upper from the upper holder and inserts 30 a left hand upper and starts the machine again, whereupon said machine will move in the opposite direction to that in which it moved while setting the lacing hooks in the right hand upper and will set a series of lacing hooks in the left hand upper and then stop.

The machine is so constructed that there is a slight motion of the holder for the upper toward and away from the lacing hook setting machine or laterally of the upper for the purpose of setting the lacing hooks equidistant from the front edge of the upper, but with this exception the upper remains stationary, while the machine which sets the 45 lacing hooks moves relatively thereto and longitudinally thereof, said machine being an organized lacing hook setting machine complete and preferably adapted to rock backwardly and forwardly with an intermittent motion, rocking in one direction for a right hand upper in setting the lacing hooks and then rocking in the opposite direction for a left hand upper and setting the lacing hooks therein.

55 The machine of this invention is further so

constructed that the extent of intermittent spacing movement of the machine, whereby the distance between the lacing hooks for a series of said lacing hooks is determined, may be readily increased or diminished by 60 simply turning a handle or wheel which is graduated to indicate the different distances between the lacing hooks. This rotation of the handle causes a change to be made in the mechanism which rocks the lacing hook setting machine, so that each step in the rocking of the machine or in the intermittent movement thereof, may be of a predetermined extent and so that the total angle through which the lacing hook setting machine swings in opposite directions may be increased or diminished at will by the operator.

The invention primarily, then, consists in an organized lacing hook setting machine 75 and mechanism to move said lacing hook setting machine relatively to a holder for the upper of a boot or shoe and longitudinally of said upper, so that while the upper remains practically stationary, the machine will 80 move bodily relatively to the upper and set a series of lacing hooks therein.

The invention further consists in improved means whereby a series of hooks or similar devices may be rapidly and accurately set on a curve corresponding approximately to the curve of the edge of a shoe upper. Broadly considered, this feature of the invention contemplates the provision of any suitable construction and arrangement of setting devices 85 and work holder which are relatively actuated to set lacing hooks or the like on a prescribed curve, it being immaterial to the invention in its broader aspects which of the parts are moved or shifted in securing the 90 proper relative movements between the setting devices and work.

The invention further consists in certain improved instrumentalities for feeding a lacing hook from the raceway to the lacing hook carrier, and further still said invention consists in the combination and arrangement of parts set forth in the following specification and particularly pointed out in the claims thereof.

Referring to the drawings, Figure 1 is a plan view of my improved lacing hook setting machine. Fig. 2 is a front elevation of the top edge gages and their means of support. Fig. 3 is a front elevation of said 105 110

ing hook setting machine, the same being partly broken away and shown in section, with the holder for the upper removed. Fig. 4 is a sectional elevation of the machine taken on line 4--4 of Fig. 1, looking toward the left in said figure. Fig. 5 is a sectional elevation taken on line 5--5 of Fig. 13, illustrating a portion of the driving shaft clutch mechanism. Fig. 6 is a sectional elevation through the upper holder and clamp taken on line 6--6 of Fig. 1. Fig. 7 is a sectional elevation taken on line 7--7 of Fig. 1, illustrating the lacing hook feeding mechanism. Fig. 8 is a detail sectional elevation taken on line 8--8 of Fig. 7. Fig. 9 is a sectional elevation taken on line 9--9 of Fig. 1, still further illustrating the lacing hook feeding mechanism. Fig. 10 is a sectional elevation taken on line 10--10 of Fig. 7 illustrating the lacing hook detent device. Fig. 11 is an enlarged front elevation of the lower portion of the raceway and a portion of the lacing hook feeding mechanism in connection therewith. Fig. 12 is a sectional elevation taken on line 12--12 of Fig. 1, illustrating a portion of the mechanism by which the lacing hook setting machine is rotated step by step. Fig. 13 is a sectional elevation taken on line 13--13 of Fig. 4. Fig. 14 is a sectional elevation taken on line 14--14 of Fig. 1, illustrating a portion of the adjusting mechanism by means of which the feeding movement of the lacing hook machine is increased or diminished. Fig. 15 is a sectional plan taken on line 15--15 of Fig. 3. Fig. 16 is a plan view of a left hand upper in full lines and a right hand upper in dotted lines, illustrating the same in the positions which they occupy with relation to the top and front edge gages. Fig. 17 is a perspective view enlarged of a portion of the instrumentalities by means of which the lacing hook setting machine is rotated. Fig. 18 is a detail sectional elevation taken on line 18--18 of Fig. 1. Fig. 19 is a detail rear elevation of one of the cam levers and the cam by which it is actuated, other parts being shown in section.

Like numerals refer to like parts throughout the several views of the drawings.

In the drawings, 20 is an organized lacing hook setting machine rotatably mounted upon a base 21. The frame 22 of the lacing hook setting machine is fastened to a ring 23 (Figs. 4 and 18) which projects downwardly through a hole 24 in the base 21 and is adapted to rotate therein, said ring being held in said base by the weight of the machine and further by a collar 25 which is split and clamped to the ring 23 by a clamp-screw 26. The driving-shaft 27 (Fig. 4) is journaled to rotate in suitable bearings 28, 29 in the ring 23, which, it will be remembered, is rigidly fastened to the frame 22 of the lacing hook setting machine, said driving shaft having a driving pulley 30 loosely mounted to rotate

thereon. Said driving pulley is rotated by means of a belt which passes partly there-around and downwardly upon opposite sides thereof to idler pulleys 31 and 32 rotatably mounted upon a stationary shaft 33 which is supported in brackets 34, 34 fast to the ring 23 (Fig. 3). The belt passes partly around the guide pulleys 31, and 32 and then toward the back of the machine in a horizontal direction, as illustrated in dotted lines (Fig. 4) and thence to a suitable driving pulley.

The pulley 30 is provided with teeth 35 upon its hub adapted to be engaged by a pin 36 adapted to slide in a clutch collar 37 which is fast to the shaft 27. A spring 38 holds said pin normally in engagement with the teeth 35 and the same is thrown out of engagement therewith by means of a lever 39, pivoted at 40 to the ring 23 and connected by a link 41 to a rocker-arm 42 fast to a rock-shaft 43 (Figs. 1 and 5). The rock-shaft 43 is journaled to rock in suitable bearings in the frame of the machine and has fastened to the rear end thereof an arm 44 (Fig. 12). The arm 44 has a cam-roll 45 journaled thereon and adapted to bear against a cam 46 fast to a gear 47 which is journaled to rotate upon a stud 48 (Fig. 4) fast to the frame of the machine.

The gear 47 meshes into a pinion gear 49 which is slidable longitudinally upon the shaft 27 and is provided with teeth adapted to engage corresponding teeth upon a clutch collar 50 which is keyed to the shaft 27. The pinion gear 49 is moved longitudinally upon the shaft 27 to bring the same into engagement with the clutch collar 50 by a lever 51 operated by a treadle rod 52 leading to a suitable treadle (not shown in the drawings), so that by operating this treadle in the proper direction the pinion gear 49 may be connected to or disconnected from the shaft 27 by the clutch collar 50, and thus said pinion and the gear 47 into which it meshes and the cam 46 fast to said gear may be rotated or stopped at the will of the operator. The gear 47 has a cam path 53 in its rear face (Figs. 4 and 12) and this cam path has a series of throws 54 and rests 55 therein.

The lacing hook setting machine, as a whole, is rotated step by step by this cam through instrumentalities which I will now proceed to describe: A cam-slide 56, formed, preferably, of a rod, slides in bearings 57, 58 (Fig. 12) and has fastened thereto a collar 59 upon which is journaled a cam roll 60 which rides in the cam path 53 (Fig. 1). Referring now to Figs. 1, 3, 4, 12 and 17, it will be seen that the slide rod 56 has a collar 61 clamped thereto (see Fig. 17). This collar has a pivotal stud 62 fast thereto upon which a collar 63 is mounted to rock. The collar 63 is slidably mounted upon a rod 64 which extends at right angles to the rod 56 and has slidably mounted thereon a collar 65 which

is pivoted upon a stud 66, the stud 66 being clamped to a collar 67. The lower end of the stud 66 projects into a slot 68 formed in the plate 69 which is fastened to the frame of the machine (Fig. 3). The collar 67 is normally stationary, but may be adjusted, as hereinafter described, to vary the relative location of the pivotal stud 66 to the stud 62.

A collar 70 is fastened to the rod 64 and is 10 adapted to rock upon a stud 71 which is fastened to a collar 72, said collar 72 being rigidly clamped to a rod 73 which extends across the machine parallel to the rod 56 and is adapted to slide in bearings 74, 74 provided in the frame 22. The rod 64, collar 63, collar 65 and collar 70 constitute a lever which is pivoted upon the stud 66 and is pivotally connected to the collar 61 by the stud 62 and to the collar 72 by the stud 71. The 20 rod 73 has gear teeth 75 formed thereon (Fig. 1) constituting a rack, which rack meshes into a pinion 76 fast to a vertical shaft 77, to the lower end of which is fastened another pinion 78 which meshes into a segment gear 79, said segment gear 79 being rigidly fastened to the base 21, preferably by screws 80, 80.

The general operation of the mechanism hereinbefore described for imparting an intermittent rotary motion to the lacing hook setting machine as a whole is as follows: The rod 56 is given an intermittent sliding movement by means of the cam 53. This intermittent sliding movement imparts an 30 intermittent rocking movement to the lever 81, said lever consisting, as hereinbefore set forth, of the collar 63, rod 64, collar 65 and collar 70. Said lever rocks upon the stud 66, the collar 65 being the immediate part 40 which rocks upon said stud, and this rocking movement of the lever as a whole imparts an intermittent sliding movement to the rack rod 73 by means of the collar 70 and the pivotal pin 71 which connects said collar to the 45 collar 72 which is rigidly fastened to the rod 73.

The intermittent sliding movement of the rod 73, it is evident, will impart an intermittent rotary movement to the pinions 76 and 50 78 and as the pinion 78 meshes into the segment gear 79, which is stationary, it is evident that this intermittent rotary movement will cause the lacing hook setting machine frame and all the parts thereon to be 55 rotated intermittently in one direction or the other, according to the direction in which the cam slide rod 56 is being moved by the cam 53.

In order to increase or diminish the angle 60 through which the lacing hook setting machine moves at each step in the intermittent movement thereof for the purpose of increasing or diminishing the distance between the lacing hooks as they are set in the 65 upper of a boot or shoe, the pivotal stud 66

of the lever 81 is made adjustable relatively to the pivotal connecting studs 62 and 71 of said lever, and this adjustment is performed by means of the mechanism illustrated in Figs. 1, 14 and 17, in which it will be seen 70 that the collar 67 is fastened to a sleeve 82 which is adapted to slide longitudinally upon a rod 83, the rod 83 being fastened to a bracket 84 fast to the frame of the machine. The sleeve 82 projects into another sleeve 85 75 to which is fastened a handle or knob 86 which has graduations 87 formed upon the periphery thereof and adjacent to an index finger 88 fast to a bracket 89, which bracket is fastened to the frame of the machine and 80 forms a support or bearing in which the sleeve 85 rotates.

A shoulder 90 on one side of said bracket and the handle 86 on the opposite side of said bracket prevent the sleeve 85 from moving 85 longitudinally thereof, but it will be understood that the same may be rotated in the bracket 89. A pin 91 is fastened to the sleeve 85 and projects into a helical slot 92 formed in the periphery of the sleeve 82, so 90 that by rotating the handle 86 it will be seen that the sleeve 85 will rotate, carrying with it the pin 91, and as said pin 91 projects into the helical slot 92 the rotation of said handle 86 and sleeve 85 will cause the sleeve 82 to 95 be moved longitudinally thereof, together with the collar 67 which is fastened thereto. As the collar 67 has fastened thereto the stud 66, it will be evident that this rotation of the handle 86 will move the stud 66 toward the 100 front or back of the machine, as the case may be, and change the relative location of said stud to the pivotal studs at the opposite ends of the lever 81, thus changing the relative movement of the rack slide 73 to the cam 105 slide 56 and consequently changing the distance through which the lacing hook setting machine will be moved at each step in the intermittent movement thereof.

The lacing hooks are placed in bulk in a 110 hopper 93, which may be of any suitable construction, and the lacing hooks are fed from said hopper down a raceway 94, the lower end of which terminates in a $\frac{1}{4}$ -turn 95 (Figs. 7 and 9). The lacing hooks descend 115 said raceway to said $\frac{1}{4}$ -turn and land at this point upon a projection 96 upon a feed finger 97. Said feed finger then delivers the lacing hook to the $\frac{1}{4}$ -turn 95 of the lower end of the raceway and also pushes said lacing hook down said $\frac{1}{4}$ -turn and onto a lacing hook carrier 98. To accomplish this result the feed finger 97 is provided with a second or upper projection 99 which contacts with the neck of the lacing hook and pushes 120 it around the $\frac{1}{4}$ -turn 95 onto the carrier 98, moving said lacing hook from a horizontal position, as shown in Fig. 7, to a vertical position, as shown in Fig. 9, with the stem of the lacing hook projecting upwardly in said 130

Fig. 9, ready to be driven through the upper and clenched therein and against an anvil 100 in a manner well known to those skilled in the art.

5 The feed finger 97 is pivoted upon a crank-pin 101 fast to a crank 102, said crank being fastened to a rock-shaft 103 which is journaled to rock in suitable bearings and has a segmental gear 104 clamped thereto and 10 meshing into a segmental lever 105, the vertical arm of which has a cam roll 106 journaled thereon and bearing against a cam 107 which is fastened to the driving shaft 27 (Fig. 4). The feed finger 97 has a slot 108 therein 15 in which is located a sliding block 109 pivoted upon a stud 110 fast to the bracket 111, so that as the lever 105 is rocked by its cam to impart a rocking movement to the gear 104 and rock-shaft 103, the crank-arm 102 will 20 be rocked from the position shown in Fig. 7 to the position shown in Fig. 9 in the direction of the arrow *a* in said Fig. 9, and this rocking movement of the crank-arm will move the lower projection 96 downwardly in 25 a substantially vertical direction at first until the lacing hook 112 shall have been delivered to the $\frac{1}{4}$ -turn 95 of the raceway. A further rocking movement of the feed finger will cause the projection 99 to engage the 30 neck of the lacing hook 112 and push the same downwardly around the $\frac{1}{4}$ -turn 95 and onto the lacing hook carrier 98. The lacing hook is now in position to be carried upwardly and set in the upper, as hereinbefore described.

The anvil 100 is adjustably fastened to the frame 22 being screw-threaded and provided with adjusting nuts 113, 113. The lacing hooks on the raceway above the $\frac{1}{4}$ -turn at 40 the lower end of said raceway are held back (see Figs. 7, 10 and 11) by a detent 133 which consists of a pin 134 having a plate 134' thereon which terminates in a finger 134" adapted to project downwardly between the 45 lowermost lacing hook on that portion of the raceway above the $\frac{1}{4}$ -turn and the lacing hook 112 which rests upon the projection 96 upon the feed finger 97. The pin 134 is adapted to slide in the bracket 111 fast to the 50 frame of the machine and is held downwardly by a spring 136. Said detent is carried upwardly out of engagement with the lacing hooks upon the raceway, as illustrated in Fig. 11, by the projection 99 upon the feed- 55 finger 97 when said finger is in the position illustrated in Fig. 7, it being understood that said projection 99 engages the under side of the plate 134' and moves the detent upwardly against the action of the spring 136, 60 at the proper time to allow the lowermost lacing hook upon that portion of the raceway extending above the $\frac{1}{4}$ -turn to move from said raceway onto the projection 96 upon the feed finger 97.

The lacing hook carrier consists of a sleeve 65 114 having a closed top 115 which forms a seat for the lacing hook to rest upon while being carried up and driven in the stock, said sleeve being cut out at 116 to admit the lacing hook 112 when it is fed thereon, said carrier consisting of a stud 117 to which the sleeve 114 is fastened. 70

The stud 117 (Fig. 4) is provided at its lower end with a bearing 118 arranged to rock upon the spherical upper end 119 of a 75 stud 120 which, in turn, is adjustably fastened to a yoke 121 pivoted to a pin 122 extending transversely through an ear 123 formed upon a collar 124 which is mounted upon a crank-pin 125 extending from the 80 forward end of the driving shaft 27 and in a direction transversely to said pin 122.

The stud 117 has screw-threaded engagement with an arm 126 (Figs. 4 and 19) which extends rearwardly from said stud and is 85 pivoted at its rear end upon screws 127, 127 which have screw-threaded engagement with a cam lever 128. A cam roll 129 journaled on the lever 128 bears against a cam 130 and is held thereagainst by a spring 131 and 90 spring pin 132 which bears directly against the lever 128. The object of the arm 126, lever 128 and cam 130 is to guide the lacing hook carrier during its upward and downward motion and also to push said lacing 95 hook carrier outwardly to disengage the same from the lacing hook after said lacing hook has been set in the upper. The lacing hook carrier 98 is first moved upwardly from the position shown in Fig. 9 to that shown in 100 Fig. 4, setting the lacing hook in the upper; it is then moved outwardly to disengage the same from the lacing hook by the arm 126 and cam lever 128. It is then moved downwardly and inwardly by the combined action 105 of the crank pin 125 on the shaft 27 and that of the lever 128, cam 130 and arm 126.

The upper 138 of the boot or shoe is held during the setting of the lacing hook upon a holder 139 (Figs. 1, 4 and 6). Said holder 110 consists of a member 140 pivoted to a stud 141 fast to the base 21. The member 140 has two brackets 142, 142 fast thereto and extending upwardly therefrom, and to these brackets are fastened a guide plate 143 and 115 a clamp plate 144. A movable clamp member 145 consists of a clamp-plate 146 supported upon arms 147, each of these arms being provided with downwardly extending stems 148 arranged to slide vertically in the 120 member 140 and being held upward normally by springs 149 to clamp the upper 138 between the plates 146 and 144. The plate 146 is lowered against the action of the spring 149 in order to remove the upper or in order to 125 insert the same between the plates 146 and 144 by a treadle (not shown in the drawings) which is connected by a treadle rod 150 to

an arm 151 fast to a rock-shaft 152 journaled to rock in bearings in the pivoted member 140 of the upper holder.

The rock-shaft 152 has two arms 153, 153 5 fast thereto which are slotted at their outer ends to straddle the lower ends of the stems 148, 148, said stems being provided with cross-pins 154, against which the outer ends of the arms 153 bear when said arms are 10 rocked downwardly by depressing the treadle, thus moving the stems 148, the arms 147, and the plate 146 downwardly to release the upper in order that it may be removed from the machine or in order that said 15 upper may be inserted between the clamp-plates 144 and 146. A spring 155 connected to the shaft 152 normally holds the guide plate 143 in engagement with a roll 156 which is arranged to rotate (Fig. 4) upon the stem 20 of the anvil 100.

The upper is positioned in the machine ready to have the first lacing hook set therein by top gages 157 and 158 and by front gages 159, 159, which front gages are fastened to the 25 clamp plate 144. The top gages 157 and 158 are pivoted at 160 and 161, respectively, to a collar 162 adapted to be clamped to the stem of the anvil 100 (Figs. 2 and 4). Each of the top gages 157 and 158 is provided with a slot 30 163 and clamped in position by screws 164, 164 which extend through said slots 163, 163 and have screw-threaded engagement with the collar 162, so that the lower ends of the gages 157 and 158 can be adjusted by means 35 of these screws 164 toward the right or left, if may be desired, as viewed from the front of the machine.

It is very essential in the operation of the machine that there shall be no backlash and 40 for this reason the vertical shaft 77 is made adjustable to insure a close fit between the teeth of the pinion 78 and the segmental gear 79. This adjustment of the shaft 77 is secured by rotatably mounting the same in a 45 sleeve 165 which, in turn, is rotatably mounted in a split hub 166 arranged to be clamped to the sleeve 165 by means of clamp-screws 167, 167 (Figs. 1, 3 and 15). The shaft 77 is eccentric to the sleeve 165 and said sleeve 50 can be readily rotated by means of a pin inserted in one of the holes 168 through a slot 169 in the hub 166.

It will be understood that the stud 120 and 55 yoke 121 form together a link which is pivoted at its lower end to the cross-pin 122 and at its upper end is connected by the ball 119 and ball bearing nut 119' to the lower end of the stud 117 upon which the lacing hook carrier sleeve 114 rests and to which it is fastened, so that the lacing hook carrier and the 60 front end of the arm 126 rest upon the upper end of said link. The ball 119 renders it possible for the link to tip in any desired direction relatively to the lacing hook carrier stud 117, so that as the crank pin 125 rotates said

link may be tipped laterally and as the lacing hook carrier is pushed out of the lacing hook said link may be tipped longitudinally relatively to the shaft 27.

Having thus specifically described the 70 construction of my improved lacing hook setting machine and also the operation of certain combinations of mechanism therein, I will now proceed to describe the general operation of the machine. Assuming the 75 organized lacing hook setting machine to be in position for a left hand upper to be inserted therein for the purpose of attaching lacing hooks thereto, the median axial line of the driving shaft 27 would be in the position indicated by the line B—B, Fig. 16. The operator then depresses the treadle connected to the treadle rod 150, thus depressing the arm 151, rocking the shaft 152 and the arms 153 thereon downwardly (Fig. 6) 80 to depress the stems 148, the arms 147 and clamp plate 146 attached to said arms, thus allowing the operator to insert the left hand upper 138' between the clamp plates 144 and 146, which she does until the front edge of 85 said upper bears against the front edge gages 159, 159. The operator holds the upper edge of the upper 138' against the lower end of the top gage 157. This she is able to do by slightly lifting the upper edge of the upper 90 138'. Thus the upper is placed in position relatively to the lacing hook carrier and the anvil so that the first lacing hook 112 may be inserted in the proper position and at the proper distance from the upper and 95 front edges of the upper 138'. The operator having thus placed the upper in the proper position for the first lacing hook to be set therein releases the treadle and allows the clamp plate 146 to clamp the upper against 100 the plate 144. The operator now depresses the treadle which is connected to the clutch lever 39 by the treadle rod 170, thus releasing the pin 36 and the spring 38 forces said pin 36 toward the right (Fig. 4) to bring the 105 same into engagement with the teeth 35 on the pulley 30, and thus lock said pulley to the driving shaft 27. Said driving shaft is now rotated by said pulley and the feed finger 97 is actuated by the lever 105 and 110 cam 107, together with the gear 104 and crank 102, to move the projection 96 thereon 115 downwardly, thus feeding the lacing hook 112 to the $\frac{1}{4}$ -turn 95, and a continuation of the downward movement of said feed finger 120 releases the detent 133, so that the same is lowered and the prong 134' passes in front of the lowermost lacing hook upon the upper part of the raceway, holding back said lacing hooks while the lacing hook 112 is being 125 moved downwardly around the $\frac{1}{4}$ -turn 95 by the upper projection 99 of the feed finger. Said upper projection pushes the lacing hook 112 onto the top 115 of the lacing hook carrier and said lacing hook carrier is then 130

moved upwardly from the position illustrated in Fig. 9 to that illustrated in Fig. 4, setting the lacing hook in the upper 138² by clenching the same against the anvil 100. 5 The lacing hook now being set in the upper, the lacing hook carrier is rocked upon the ball 119 by the arm 126, lever 128 and cam 130 which pushes the top 115 of the sleeve 114 out of engagement with the head of the 10 lacing hook. The lacing hook carrier as a whole is then moved downwardly by the rotation of the shaft 27 and the crank-pin 125, and simultaneously with this downward movement the lacing hook carrier is brought 15 inwardly by the lever 128, cam 130 and arm 126 to the position illustrated in Fig. 7, ready to receive another lacing hook. After the lacing hook 112 has been set in the upper, as hereinbefore described, the cam 53 actuates the cam-slide 56 to rock the cam lever 81 on its pivotal stud 66, thus moving the rack-slide 73 in the opposite direction and rocking the lacing hook setting machine, through the gearing 76, 78 and 79, until the 20 median axial line of the driving shaft 27 assumes the position of the line C—C, Fig. 16. One of the rests 55 in the cam path 53 now causes the machine to become stationary as to rotary movement thereof and another 25 lacing hook 112² is fed and driven in the upper.

The operations hereinbefore described are again repeated and the lacing hook 112² is driven in the upper. Said operations are 30 again repeated and the lacing hook 112³ is driven in the upper 138², this being the complete number of lacing hooks which it is intended to set in the upper. The gear 47, with the cam 46, having made a half rotation 35 the cam roll 45 moves upwardly into one of the recesses in said cam 46, rocks the shaft 43 and the arm 42 which depresses the link 41 and rocks the lever 39, to release the clutch 37 and allow the pulley 30 to rotate 40 freely upon the shaft 27 without rotating the same, whereupon the rotation of the lacing hook setting machine upon its base is stopped. The operator now depresses the treadle connected to the arm 151, thus opening the upper 45 per clamps and removes the upper from the machine. A right hand upper 138² is now placed in the machine to have lacing hooks inserted therein, as illustrated in dotted lines (Fig. 16). The upper edge of said upper 50 138² is placed against the top gage 158 and against the front gages 159, 159. Having released the treadle to clamp the upper 138² in the upper holder, the operator now starts the machine, as hereinbefore described, 55 and the lacing hooks are driven from the right toward the left in a reverse order to that hereinbefore described with relation to the upper 138². When the lacing hooks have been driven in the right hand upper by

the rotation of the machine and the operation of the setting and lacing hook feeding mechanisms as hereinbefore described with relation to the setting of the lacing hooks in the upper 138², the machine comes to a stop by the clutch 37 being thrown out, as hereinbefore described, and the operator then removes the right hand upper from the machine. The machine is now in position to set lacing hooks in a left hand upper and thus alternately the machine sets lacing 7 hooks in a right hand upper and a left hand upper.

To increase or diminish the distance between the lacing hooks in a series, the pivot 66 of the lever 81 is moved toward or away 80 from the pivotal studs at the opposite ends of said lever by rotating the knob or handle 86 until the graduation 87, corresponding to the distance desired between the lacing 85 hooks, alines with the index finger 88 and the machine will then be set to rotate said machine intermittently, at each step, the distance required between the lacing hooks.

The guide-plate 143 is made of the proper curve or formation to rock the upper holder upon its pivot 141 the required distance so that the lacing hooks shall be set at the correct distance from the front edge of the upper, this guide plate being necessary to make up for the difference between the curve on 90 the front edge of the upper and the curve described by the anvil and lacing hook carrier which is concentric with the vertical median axial line of the ring 23, or the axial line about which the lacing hook machine rotates. Thus by having the guide-plate 143 of suitable outline, the upper will always be held in just the right position for the lacing hooks to be set at the same distance from the front edge of said upper.

While I have described my invention as particularly adapted to set lacing hooks in the uppers of boots and shoes, it is evident that the same may be used for setting eyelets, rivets and the like without departing from 100 the spirit of my invention.

What I claim and desire by Letters Patent to secure is:

1. In a machine for setting lacing hooks in the upper of a boot or shoe, a holder for 115 said upper, mechanism adapted to set lacing hooks in an upper held in said holder, a stationary base upon which said mechanism is movably mounted, and spacing mechanism adapted to impart an intermittent movement to said lacing hook setting mechanism, longitudinally of said upper.

2. In a machine for setting lacing hooks or the like in the upper of a boot or shoe, a holder for said upper, mechanism adapted to 125 set lacing hooks or the like in an upper held in said holder, and spacing mechanism adapted to impart an intermittent move-

ment to said lacing hook setting mechanism in a predetermined curvilinear path, longitudinally of said upper.

3. In a machine for setting lacing hooks or the like in the upper of a boot or shoe, a holder for said upper, mechanism adapted to set lacing hooks or the like in an upper held in said holder and spacing mechanism adapted to impart an intermittent movement to said lacing hook setting mechanism in a predetermined curvilinear path, longitudinally of said upper and alternately in opposite directions.

4. In a machine for setting lacing hooks or the like in the upper of a boot or shoe, means adapted to hold said upper, means adapted to set lacing hooks or the like in said upper, and instrumentalities adapted to change the relative location of said upper to said lacing hook setting means, both laterally and longitudinally of said upper, whereby said lacing hooks may be set therein in a predetermined curvilinear path.

5. In a machine for setting lacing hooks in the upper of a boot or shoe, a holder for said upper, mechanism adapted to set lacing hooks in an upper held in said holder and spacing mechanism adapted to impart an intermittent movement to said lacing hook setting mechanism longitudinally of said upper and alternately in opposite directions.

6. In a machine for setting lacing hooks in the upper of a boot or shoe, a holder for said upper, mechanism adapted to set lacing hooks in an upper held in said holder, spacing mechanism adapted to impart an intermittent movement to said lacing hook setting mechanism, longitudinally of said upper, and means to move said holder and the upper held thereon laterally of said upper.

7. In a machine for setting lacing hooks in the upper of a boot or shoe, a holder for said upper, mechanism adapted to set lacing hooks in an upper held in said holder, spacing mechanism adapted to impart an intermittent movement to said lacing hook setting mechanism, longitudinally of said upper, and means to automatically throw said setting and spacing mechanisms out of action, after a pre-determined number of lacing hooks have been set in said upper.

8. In a machine for setting lacing hooks in the upper of a boot or shoe, a holder for said upper, mechanism adapted to set lacing hooks in an upper held in said holder, spacing mechanism adapted to impart an intermittent movement to said lacing hook setting mechanism, longitudinally of said upper, and means to throw said spacing mechanism out of action, while said setting mechanism remains in action.

9. In a machine for setting lacing hooks in the upper of a boot or shoe, a holder for said upper, mechanism adapted to set lacing hooks in an upper held in said holder, a sta-

tionary base upon which said mechanism is movably mounted, spacing mechanism adapted to impart an intermittent movement to said lacing hook setting mechanism, longitudinally of said upper, and means to adjust said spacing mechanism, to vary the distance which said setting mechanism shall move at each step of the intermittent movement thereof.

10. In a machine for setting lacing hooks in the upper of a boot or shoe, a holder for said upper, mechanism adapted to set lacing hooks in an upper held in said holder, spacing mechanism adapted to impart an intermittent movement to said lacing hook setting mechanism longitudinally of said upper and alternately in opposite directions, and means to adjust said spacing mechanism, to vary the distance which said setting mechanism shall move at each step of the intermittent movement thereof.

11. In a machine for setting lacing hooks in the upper of a boot or shoe, a holder for said upper, mechanism adapted to set lacing hooks in an upper held in said holder, spacing mechanism adapted to impart an intermittent movement to said lacing hook setting mechanism longitudinally of said upper and alternately in opposite directions, and means to move said holder and the upper held thereon laterally of said upper.

12. In a machine for setting lacing hooks in the upper of a boot or shoe, a holder for said upper, mechanism adapted to set lacing hooks in an upper held in said holder, instrumentalities adapted to feed lacing hooks to said setting mechanism, and spacing mechanism adapted to impart an intermittent movement to said lacing hook setting and feeding mechanisms longitudinally of said upper.

13. In a machine for setting lacing hooks in the upper of a boot or shoe, a holder for said upper, mechanism adapted to set lacing hooks in an upper held in said holder, instrumentalities adapted to feed lacing hooks to said setting mechanism, and spacing mechanism adapted to impart an intermittent movement to said lacing hook setting and feeding mechanisms, longitudinally of said upper and alternately in opposite directions.

14. In a machine for setting lacing hooks in the upper of a boot or shoe, a holder for said upper, mechanism adapted to set lacing hooks in an upper held in said holder, instrumentalities adapted to feed lacing hooks to said setting mechanism, spacing mechanism adapted to impart an intermittent movement to said lacing hook setting and feeding mechanisms longitudinally of said upper, and means to move said holder and the upper held thereon laterally of said upper.

15. In a machine for setting lacing hooks in the upper of a boot or shoe, a holder for said upper, mechanism adapted to set lacing hooks in an upper held in said holder, instru-

5 mentalities adapted to feed lacing hooks to said setting mechanism, spacing mechanism adapted to impart an intermittent movement to said lacing hook setting and feeding mechanisms, longitudinally of said upper and alternately in opposite directions, and means to move said holder and the upper held thereon laterally of said upper.

16. In a machine for setting lacing hooks 10 in the upper of a boot or shoe, a holder for said upper, mechanism adapted to set lacing hooks in an upper held in said holder, instrumentalities adapted to feed lacing hooks to said setting mechanism, spacing mechanism 15 adapted to impart an intermittent movement to said lacing hook setting and feeding mechanisms longitudinally of said upper, and means to automatically throw said setting, spacing and feeding mechanisms out of action 20 after a pre-determined number of lacing hooks have been set in said upper.

17. In a machine for setting lacing hooks in the upper of a boot or shoe, a holder for said upper, mechanism adapted to set lacing 25 hooks in an upper held in said holder, instrumentalities adapted to feed lacing hooks to said setting mechanism, spacing mechanism adapted to impart an intermittent movement to said lacing hook setting and feeding mechanisms longitudinally of said upper and 30 means to throw said spacing mechanism out of action while said setting and feeding mechanisms remain in action.

18. In a machine for setting lacing hooks 35 in the upper of a boot or shoe, a holder for said upper, mechanism adapted to set lacing hooks in an upper held in said holder, instrumentalities adapted to feed lacing hooks to said setting mechanism, spacing mechanism 40 adapted to impart an intermittent movement to said lacing hook setting and feeding mechanisms longitudinally of said upper, and means to adjust said spacing mechanism to vary the distance which said setting and 45 feeding mechanisms shall move at each step of the intermittent movement thereof.

19. In a machine for setting lacing hooks 50 in the upper of a boot or shoe, a holder for said upper, mechanism adapted to set lacing hooks in an upper held in said holder, instrumentalities adapted to feed lacing hooks to said setting mechanism, spacing mechanism adapted to impart an intermittent movement to said lacing hook setting 55 and feeding mechanisms, longitudinally of said upper and alternately in opposite directions, and means to adjust said spacing mechanism to vary the distance which said setting and feeding mechanisms shall move 60 at each step of the intermittent movement thereof.

20. In combination, a lacing hook setting 65 machine, a stationary base upon which said lacing hook setting machine is movably mounted, a holder for the upper of a boot or

shoe, and instrumentalities adapted to move said lacing hook setting machine on said base, longitudinally of said upper, whereby a series of lacing hooks may be set therein.

21. In combination, an organized lacing hook setting machine, a holder for the upper of a boot or shoe, instrumentalities adapted to move said machine longitudinally of said upper, whereby a series of lacing hooks may be set therein, and means to move said holder 7 and the upper held thereon laterally of said upper.

22. In combination, an organized lacing hook setting machine, a stationary base upon which said lacing hook setting machine is rotatably mounted, a holder for the upper of a boot or shoe mounted upon said base, and instrumentalities adapted to rotate said machine on said base.

23. In combination, an organized lacing hook setting machine, a stationary base upon which said lacing hook setting machine is rotatably mounted, a holder for the upper of a boot or shoe mounted upon said base and instrumentalities adapted to impart an intermittent rotary motion to said machine on said base.

24. In combination, an organized lacing hook setting machine, a stationary base upon which said lacing hook setting machine is rotatably mounted, a holder for the upper of a boot or shoe mounted upon said base, and instrumentalities adapted to impart an intermittent rotary motion to said machine on said base alternately in opposite directions.

25. In combination, an organized lacing hook setting machine, a stationary base upon which said lacing hook setting machine is rotatably mounted, a holder for the upper of a boot or shoe mounted upon said base, instrumentalities adapted to impart an intermittent rotary motion to said machine on said base, and mechanism to stop said rotary motion when said machine has rotated through a predetermined angle.

26. In combination, an organized lacing hook setting machine, a stationary base upon which said lacing hook setting machine is rotatably mounted, a holder for the upper of a boot or shoe mounted upon said base, instrumentalities adapted to impart an intermittent rotary motion to said machine on said base, mechanism to stop said rotary motion when said machine has rotated through a predetermined angle, and means to vary the size of said angle.

27. In combination, an organized lacing hook setting machine, a stationary base upon which said lacing hook setting machine is rotatably mounted, a holder for the upper of a boot or shoe mounted upon said base, instrumentalities adapted to rotate said machine on said base, and means to move said holder and the upper held thereon laterally relatively of said upper.

28. In a lacing hook setting machine, a holder for the upper of a boot or shoe, consisting of a pivotally mounted member, a clamp member movable on said pivotally mounted member, and adapted to clamp an upper thereto, and means to move said holder and the upper held thereon laterally relatively of said upper.
29. In combination, an organized lacing hook setting machine, and a stationary base upon which said lacing hook setting machine is rotatably mounted; in combination with a holder for the upper of a boot or shoe pivoted to said base, and a guide plate fast to said holder, and adapted to bear against a portion of said lacing hook setting machine.
30. In combination, an organized lacing hook setting machine, and a stationary base upon which said lacing hook setting machine is rotatably mounted; in combination with a holder for the upper of a boot or shoe pivoted to said base, a guide plate fast to said holder, and adapted to bear against a portion of said lacing hook setting machine, and a spring acting to hold said guide plate against a portion of said lacing hook setting machine.
31. In combination, an organized lacing hook setting machine, a stationary base upon which said lacing hook setting machine is rotatably mounted, and mechanism to rotate said machine on said base, consisting of a segmental gear fast to said base, and gearing meshing into said segmental gear and rotatably mounted on said lacing hook setting machine.
32. In combination, an organized lacing hook setting machine, a stationary base upon which said lacing hook setting machine is rotatably mounted, mechanism to rotate said machine on said base, consisting of a segmental gear fast to said base, and gearing meshing into said segmental gear and rotatably mounted on said lacing hook setting machine, a cam rotatably mounted on said lacing hook setting machine and instrumentalities operated by said cam to rotate said gearing.
33. In combination, an organized lacing hook setting machine, a stationary base upon which said lacing hook setting machine is rotatably mounted, mechanism to rotate said machine on said base, consisting of a segmental gear fast to said base, and gearing meshing into said segmental gear and rotatably mounted on said lacing hook setting machine, a cam having a cam path with a series of rests and throws therein, rotatably mounted on said lacing hook setting machine and instrumentalities operated by said cam adapted to impart intermittent rotary motion to said gearing.
34. In combination, an organized lacing hook setting machine, a stationary base upon which said lacing hook setting machine is rotatably mounted, mechanism to rotate said machine on said base, consisting of a segmental gear fast to said base, and gearing meshing into said segmental gear and rotatably mounted on said lacing hook setting machine, a cam having a cam path with a series of rests and throws therein, rotatably mounted on said lacing hook setting machine, and instrumentalities operated by said cam adapted to impart an intermittent rotary motion to said gearing.
35. In combination, an organized lacing hook setting machine, a stationary base upon which said lacing hook setting machine is rotatably mounted, mechanism to rotate said machine on said base, consisting of a segmental gear fast to said base, and gearing meshing into said segmental gear and rotatably mounted on said lacing hook setting machine, a cam having a cam path with a series of rests and throws therein, rotatably mounted on said lacing hook setting machine, and instrumentalities operated by said cam adapted to impart an intermittent rotary motion to said gearing.
36. In combination, an organized lacing hook setting machine including a driving shaft, a stationary base upon which said lacing hook setting machine is rotatably mounted, and mechanism to rotate said machine on said base, consisting of a segmental gear fast to said base, and gearing meshing into said segmental gear and rotatably mounted on said lacing hook setting machine, a cam rotatably mounted on said lacing hook setting machine and instrumentalities operated by said cam to rotate said gearing, gearing connecting said driving shaft and cam and a clutch adapted to connect and disconnect said last named gearing to and from said shaft respectively.
37. An organized lacing hook setting machine, a base upon which said machine is rotatably mounted, mechanism adapted to impart a rotary motion thereto, said lacing hook setting machine comprising in its construction a driving shaft, a pulley loosely mounted thereon and a clutch adapted to fasten said pulley to said shaft.
38. An organized lacing hook setting machine, a base upon which said machine is rotatably mounted, mechanism adapted to impart a rotary motion thereto, said lacing hook setting machine comprising in its construction a driving shaft, a pulley loosely mounted thereon, a clutch adapted to fasten said pulley to said shaft, a cam rotatably mounted on said machine, and mechanism operated by said cam adapted to operate said clutch, to fasten said pulley to said shaft, and to unfasten said pulley from said shaft.

39. An organized lacing hook setting machine, a base upon which said machine is rotatably mounted, mechanism adapted to impart a rotary motion thereto, said lacing hook setting machine comprising in its construction a driving shaft, a pulley loosely mounted thereon a clutch adapted to fasten said pulley to said shaft, a cam rotatably mounted on said machine, mechanism operated by said cam adapted to operate said clutch, to fasten said pulley to said shaft, and to unfasten said pulley from said shaft, gearing connecting said driving shaft to said cam, and an independently operated clutch connecting said last named gearing to said shaft.
40. An organized lacing hook setting machine, a stationary base upon which said lacing hook setting machine is rotatably mounted, mechanism to rotate said machine on said base, consisting of a segmental gear fast to said base, and gearing meshing into said segmental gear and rotatably mounted on said lacing hook setting machine, a cam rotatably mounted on said lacing hook setting machine, instrumentalities operated by said cam to rotate said gearing, said instrumentalities consisting of a cam slide, operated by said cam, a rack slide meshing into said gearing, and a lever connected at its opposite ends to said slides.
41. An organized lacing hook setting machine, a stationary base upon which said lacing hook setting machine is rotatably mounted, mechanism to rotate said machine on said base, consisting of a segmental gear fast to said base, and gearing meshing into said segmental gear and rotatably mounted on said lacing hook setting machine, a cam rotatably mounted on said lacing hook setting machine, instrumentalities operated by said cam to rotate said gearing, said instrumentalities consisting of a cam slide, operated by said cam, a rack slide meshing into said gearing, a lever connected at its opposite ends to said slides, a pivot for said lever, and means to adjust said pivot relatively to said slides, whereby the angular movement of said lacing hook setting machine may be varied.
42. An organized lacing hook setting machine, a stationary base upon which said lacing hook setting machine is rotatably mounted, mechanism to rotate said machine on said base, consisting of a segmental gear fast to said base, and gearing meshing into said segmental gear and rotatably mounted on said lacing hook setting machine, a cam having a cam path with a series of rests and throws therein rotatably mounted on said lacing hook setting machine, instrumentalities operated by said cam adapted to impart an intermittent rotary motion to said gearing, said instrumentalities consisting of a cam slide, operated by said cam to impart an intermittent reciprocatory motion thereto, a rack slide meshing into said gearing, and a lever connected at its opposite ends to said slides, whereby an intermittent rotary motion is imparted to said lacing hook setting machine.
43. An organized lacing hook setting machine, a stationary base upon which said lacing hook setting machine is rotatably mounted, mechanism to rotate said machine on said base, consisting of a segmental gear fast to said base, and gearing meshing into said segmental gear and rotatably mounted on said lacing hook setting machine, a cam having a cam path with a series of rests and throws therein rotatably mounted on said lacing hook setting machine, instrumentalities operated by said cam adapted to impart an intermittent rotary motion to said gearing, said instrumentalities consisting of a cam slide, operated by said cam to impart an intermittent reciprocatory motion thereto, a rack slide meshing into said gearing, and a lever connected at its opposite ends to said slides, a pivot for said lever, and means to adjust said pivot relatively to said slides, whereby the angle through which said lacing hook setting machine is moved at each step of its intermittent movement, may be increased or diminished.
44. In a lacing hook setting machine, a race-way terminating at the bottom thereof in a $\frac{1}{4}$ turn adapted to guide a lacing hook from a horizontal to a vertical position, a lacing hook carrier at the lower end of said $\frac{1}{4}$ turn, and a feed finger having a projection thereon adapted to receive a hook from the portion of said race-way above said $\frac{1}{4}$ turn, and deliver it to said $\frac{1}{4}$ turn and another projection on said feed finger adapted to push said lacing hook down said $\frac{1}{4}$ turn and onto said carrier.
45. In a lacing hook setting machine, a race-way terminating at the bottom thereof in a $\frac{1}{4}$ turn adapted to guide a lacing hook from a horizontal to a vertical position, a lacing hook carrier at the lower end of said $\frac{1}{4}$ turn, and a feed finger having a projection thereon adapted to receive a hook from the portion of said race-way above said $\frac{1}{4}$ turn, mechanism to move said finger downwardly to deliver said hook to said $\frac{1}{4}$ turn, said finger having another projection thereon, which said mechanism is adapted to move downwardly, to engage the hook on said $\frac{1}{4}$ turn and move the same along said $\frac{1}{4}$ turn and onto said carrier.
46. In a lacing hook setting machine, a race-way terminating at the bottom thereof in a $\frac{1}{4}$ turn adapted to guide a lacing hook from a horizontal to a vertical position, a lacing hook carrier at the lower end of said $\frac{1}{4}$ turn, and a feed finger having a projection thereon adapted to receive a hook from the portion of said race-way above said $\frac{1}{4}$ turn and move the same along said $\frac{1}{4}$ turn and onto said carrier.

turn, a crank upon which said feed finger is pivoted, and a guide pin upon which said feed finger is slidably and rotatably mounted, whereby said finger is moved downwardly to 5 deliver said hook to said $\frac{1}{4}$ turn, said finger having another projection thereon, which said mechanism is adapted to move downwardly, to engage the hook on said $\frac{1}{4}$ turn and move the same along said $\frac{1}{4}$ turn and 10 onto said carrier.

47. In a lacing hook setting machine, a carrier for a lacing hook, an arm to which said carrier is fastened, and instrumentalities adapted to impart a combined reciprocatory and rocking movement to said arm, in the same plane.

48. In a lacing hook setting machine, a carrier for a lacing hook consisting of a sleeve having a top and provided with a recess in 20 one side thereof adapted to receive the head of a lacing hook and a stud fast to said sleeve, an arm with which said stud has screw threaded engagement, and instrumentalities adapted to impart a combined reciprocating 25 movement to said arm.

49. In a lacing hook setting machine, a carrier for a lacing hook, an arm to which said carrier is fastened extending horizontally and rearwardly therefrom, a lever upon 30 which the rear end of said arm is pivotally supported and a link upon one end of which the front end of said arm is pivotally supported.

50. In a lacing hook setting machine, a carrier for a lacing hook, an arm to which said carrier is fastened extending horizontally and rearwardly therefrom, a lever upon 35 which the rear end of said arm is pivotally supported, a link, upon one end of which the front end of said arm is pivotally supported, a collar pivotally connected to the other end of said link and a crank upon which said collar is mounted.

51. In a lacing hook setting machine, a carrier for a lacing hook, an arm to which said carrier is fastened extending horizontally and rearwardly therefrom, a lever upon 45 which the rear end of said arm is pivotally supported a link upon one end of which the front end of said arm is pivotally supported,

and means to impart a rocking movement to said lever.

52. In a lacing hook setting machine, a carrier for a lacing hook consisting of a sleeve having a top and provided with a recess in 55 one side thereof adapted to receive the head of a lacing hook, a stud fast to said sleeve, an arm with which said stud has screw threaded engagement, extending rearwardly therefrom, a link the upper end of which is ball-shaped and adapted to fit in a corresponding recess provided in the lower end of said stud, a collar pivotally connected to the other end of said link and a crank upon which said collar is mounted.

53. In a lacing hook setting machine, a holder for the upper of a boot or shoe and means to move said holder and the upper held thereon laterally relatively of said upper for the purpose specified.

54. In a lacing hook setting machine a pivotally mounted holder for the upper of a boot or shoe and means to rock said holder and the upper held thereon laterally relatively of 70 said upper for the purpose specified.

55. A machine for setting lacing hooks and the like, in the upper of a boot or shoe, having in combination, lacing hook setting means, a holder for an upper of a boot or shoe and means to impart a relative motion 80 to said holder and lacing hook setting means both laterally and longitudinally of said upper, whereby lacing hooks may be set in said upper in a curve corresponding to the front edge of said upper.

56. A machine for setting lacing hooks and the like, having, in combination, setting devices, a work holder, and mechanism acting to relatively actuate the holder and setting devices to set a series of hooks or the like on a 90 curve corresponding substantially to the curve of the edge of the work, substantially as described.

In testimony whereof I have hereunto set my hand in presence of two subscribing witnesses.

WARREN F. FRASER.
